ATTORNEYS

Patented Dec. 9, 1924.

UNITED STATES PATENT OFFICE.

EARL W. WOOD, OF LOS ANGELES, CALIFORNIA.

PAPER-HANDKERCHIEF PACKAGE.

Application filed August 19, 1922. Serial No. 582,984.

To all whom it may concern:

Be it known that I, EARL W. WOOD, a citizen of the United States, residing at Los Angeles, in the county of Los Angeles and State of California, have invented new and useful Improvements in Paper-Handkerchief Packages, of which the following is a specification.

This invention relates to toilet articles and more particularly to paper handkerchief packages.

It is an object of the present invention to provide a compact, substantial, practicable and inexpensive package consisting of a foldable receiver and a pad of paper squares of suitable material, preferably of paper, to be utilized as handkerchiefs.

It is an object further to provide a receiver capable of being readily carried in the pocket and which is provided with a flap whereby a pad of paper handkerchiefs can be neatly covered and protected and which at the same time enables the ready removal of the handkerchiefs as desired.

Another object is to provide a handkerchief package incorporating means for perfuming the handkerchiefs.

Another object is to provide a handkerchief receiver and holder having an individual pocket for receiving used handkerchiefs as may be necessary.

Other objects and advantages will be made manifest in the following specification of the embodiments of the invention illustrated in the accompanying drawings, wherein:

Figure 1 is a perspective of the package in closed position.

Figure 2 is a perspective showing the handkerchief covering flap unfolded to expose the paper handkerchiefs and showing the spare pocket flap opened.

Figure 3 is a section from top to bottom of the closed package.

Figure 4 is a transverse section on line 4-4 of Figure 3.

Figure 5 is a plan of the blank of the corner ear.

Figure 6 is a perspective of a portion of the receiver showing the method of attaching the blank to the receiver body.

Figure 7 is a perspective of the front of a modified form of package.

Figure 8 is a perspective of the back of the modified package.

Figure 9 is a perspective of the unfolded

package showing a four section handkerchief.

Figure 10 is a section from top to bottom of the folded package of Figure 7.

Figure 11 is a plan of a six section handkerchief package.

The device is preferably built up of flexible material, such, for instance, as tenacious paper having the desirable wearing quality and the main body consists of an inner or back sheet 2, the bottom of which is rolled at 3 and extends upwardly to form a flap 4, the corners of which may be tucked in under retaining devices in the form of ears 5, one of the blanks of which is shown in Figure 5 as having a lug 6 adapted to be folded in and adhesively secured to the contiguous overhanging forward portion of the upper end of the back 2. This upper end has a fold 2^a transversely across the top of the receiver and this is folded forwardly and down as at 2^b and is then reversed to form an inner strip 2^c. The superposed folds 2^b and 2^c form therebetween a shallow channel which may be filled with any suitable perfuming material, such, for instance, as a sachet powder which may sift through a line of apertures 7 provided in the crease along the folds 2^b and 2^c.

Between the folded strip 2^c and the adjacent portion of the back 2 there is firmly held, preferably adhesively, the top end of a pad of leaves or sheet 10 preferably of a suitable paper stock that may be adapted for handkerchief service. The upper ends of the sheets or handkerchiefs 10 are perforated as at 11 to facilitate the separation of each of the handkerchiefs from the fastened stub of the pad.

The handkerchiefs are of suitable proportions and are preferably folded medially so as to be bent up and then covered by the overlaid outside flap 4.

Ordinarily the handkerchiefs after being used may be discarded but there may be certain occasions when it would not be practicable to discard the handkerchiefs and in such case they may be concealed in a pocket provided for that purpose and forming a portion of the package.

The pocket consists of an outer wall 12 having pleated top and bottom transverse flanges 13 with inturned lips 14 adhesively or otherwise secured to the back 2. One end of the outer wall 12 may be provided with an inwardly turned flap 15, as shown

in Figure 4, to form a bottom closure for the pocket and the opposite end of the wall 12 is provided with an inwardly turned flap 16 which has a pull piece or finger strip 17. 5 This enables the pulling of the flap 16 outwardly to uncover the end of the waste pocket under the wall 12 so as to permit the insertion of the used handkerchiefs after which the cover flap 16 may be restored to 10 covering position.

A somewhat modified form of the invention is illustrated in Figures 7 to 11 inclusive. In this form of the invention the pad of handkerchiefs comprises a number of 15 handkerchief sheets 10^a having right angularly intersecting or crossing fold lines *a* and *b* of Figure 9 and *a*, *b* and *c* of Figure 11. The handkerchief sheet of Figure 9 consists of four quadrangles adapted to be 20 folded in compact position one upon the other as to each handkerchief, while in Figure 11 a handkerchief sheet consists of six quadrangular sections. The sheet of Figure 11 provides a central stub portion 10^b having 25 a row of perforations 11 for the medial set of sections of each handkerchief, there being two lateral sections flanking the medial sections on each side.

Further embodiments, modifications and 30 variations may be resorted to within the spirit of the invention as here claimed.

What is claimed is:

1. A paper handkerchief and cover structure comprising a pad of sheets attached at 35 one end to the cover, said pad being transversely folded on itself, and said cover including a flap to cover the folded pad, the cover having corner ears under which the flap corners are retainable.
2. A package consisting of a receiver 40 structure, and a pad of paper handkerchiefs

attached to said structure, the receiver structure including a stub holding part and a flap end to fold up over the folded pad, the stub holding end of the receiver having retaining means for holding the flap in closed position, said retaining means consisting of ears fastened to the top of the receiver and under which the corners of the flap may be tucked in. 45

50 3. A package consisting of a receiver structure, and a pad of paper handkerchiefs attached to said structure, the receiver structure including a back having its upper transverse edge double folded to form a channel overlying the applied pad and adapted to receive a perfuming substance. 55

4. A package consisting of a receiver structure, and a pad of paper handkerchiefs attached to said structure, the receiver structure including a back having its upper transverse edge double folded to form a channel overlying the applied pad and adapted to receive a perfuming substance, the double folded portion having apertures through 60 which the said substance may sift. 65

5. A package consisting of a receiver structure, and a pad of paper handkerchiefs attached to said structure, the said receiver being provided with a spare pocket at its 70 back to receive used handkerchiefs.

6. A package consisting of a receiver structure, and a pad of paper handkerchiefs attached to said structure, the said receiver being provided with a spare pocket at its 75 back to receive used handkerchiefs, said spare pocket having a closed end and having its opposite end provided with a pull flap for closing its end of the pocket.

In testimony whereof I have signed my 80 name to this specification.

EARL W. WOOD.
